US00D445096S

(12) **United States Design Patent** (10) Patent No.: **US D445,096 S**
Wallace (45) Date of Patent: ** Jul. 17, 2001

(54) **REMOVABLE MEMORY CARD FOR USE WITH PORTABLE ELECTRONIC DEVICES**

(75) Inventor: **Robert F. Wallace**, Sunnyvale, CA (US)

(73) Assignee: **SanDisk Corporation**, Sunnyvale, CA (US)

(**) Term: **14 Years**

(21) Appl. No.: **29/085,918**

(22) Filed: **Apr. 1, 1998**

(51) LOC (7) Cl. **14-02**

(52) U.S. Cl. **D14/117**

(58) Field of Search D14/114, 117; 235/492, 487, 380-1, 441; 365/52; 463/43-47

(57) **CLAIM**

The ornamental design for a removable memory card for use with portable electronic devices, as shown and described.

DESCRIPTION

FIG. 1 is an isometric view of a removable memory card for use with portable electronic devices that incorporates a first embodiment of the new design, showing the card's top, front side and left side;

FIG. 2 is a top plan view of the memory card first embodiment;

FIG. 3 is a left side elevational view of the memory card first embodiment;

FIG. 4 is a front side elevational view of the memory card first embodiment;

FIG. 5 is a bottom plan view of the memory card first embodiment;

FIG. 6 is a right side elevational view of the memory card first embodiment;

FIG. 7 is a rear side elevational view of the memory card first embodiment;

FIG. 8 is an isometric view of a removable memory card for use with portable electronic devices that incorporates a second embodiment of the new design, showing the card's top, front side and left side;

FIG. 9 is a bottom plan view of the memory card second embodiment;

FIG. 10 is a right side elevational view of the memory card second embodiment;

FIG. 11 is a front side elevational view of the memory card second embodiment;

FIG. 12 is a top plan view of the memory card second embodiment;

FIG. 13 is a left side elevational view of the memory card second embodiment; and,

FIG. 14 is a rear side elevational view of the memory card second embodiment.
